SOLOMON M. CUTTER, OF READING, MASSACHUSETTS, ASSIGNOR, BY MESNE ASSIGNMENTS, TO UNITED SHOE MACHINERY COMPANY, A CORPORATION OF NEW JERSEY.

WIRE-FEEDING MECHANISM FOR NAILING-MACHINES.

960,278.

Specification of Letters Patent.

Patented June 7, 1910.

Application filed April 19, 1898. Serial No. 678,149.

To all whom it may concern:

Be it known that I, SOLOMON M. CUTTER, of Reading, county of Middlesex, State of Massachusetts, have invented an Improvement in Wire-Feeding Mechanisms for Nailing-Machines, of which the following description, in connection with the accompanying drawings, is a specification, like letters on the drawings representing like parts.

This my invention relates to mechanism in nailing machines whereby a continuous wire is fed and nails severed from the wire and carried into position to be driven into stock.

Other features of my invention consist of the simple means whereby the wire-feeding mechanism is operated, and of the combination of parts connected with the wire-feeding, and combined nail-carrying and wire-cutting mechanism.

In the accompanying drawings: Figure 1 is a front view of the upper part of a machine embodying my invention. Fig. 2, is also, a front view of the same machine, but for more clearness the front plates, covering part of the mechanism, are removed. Fig. 3 is a side view of an adjustable stop, whereby the extent of the feeding of the wire is determined. Fig. 4 is a top view of the wire-feeding mechanism, Fig. 5 is a sectional view of the wire-feeding mechanism.

The same letters of reference indicate similar parts in all the figures in the drawings.

The driving shaft *a* carries a cam *a'* which is provided with a crank-pin *a''* and with a cam-groove *b*, shown in dotted lines, and has the width of its periphery divided into two independent parts *b'* and *b''*. The part *b'* operates a lever *d''*, which is fulcrumed to the frame *c* at *c'* and has a projection adapted to engage the awl-carrying bar *c''* and move the latter toward the driver *d* after the awl *e* is moved into the stock, and thereby forcing the awl to feed the stock.

A spring *d'* is attached to the awl-carrying bar and to the frame, and the tendency of this spring is to move the awl-carrying bar from the driver and thereby, also, tending to hold the lever *d''* in contact with the cam *a'*. The awl-carrying bar *c''* carries the awl *e* in a well known manner, and is loosely attached to the free end of a lever *e'*, which is hung on a stud *e''* and provided with a cam-roller *f* engaged by the cam-

groove *b*, and thereby the free end of the lever is moved up and down and forces the awl to puncture the stock. Another lever *f'* is fulcrumed to the frame at *f''* and is periodically operated by the operating part *b''* of the cam, for the purpose as herein-after set forth, and which lever is held in contact with the cam by a spring *g*. The driver *d* is carried in a block or driver bar *g'* which is given a reciprocating motion by *g''*, which is hung on the crank-pin *a''*.

These mechanisms, so far as described, are the same as in the Letters Patent No. 582,579, issued to me May 11, 1897, in nailing machines adapted to drive nails severed from a comb-shaped strip.

The wire *j''* used in this machine can be carried on a reel, or by any other suitable means, and is shown extended through a hole in a block *h*, the hole being shaped to present a shoulder to sustain one side of the wire. This hole contains a spring-pressed pawl or pawls *h'* to grip and hold the side of the wire opposite that sustained by the shoulder of said block as the latter is being moved downwardly to feed the wire, the pawls sliding over the wire as the block is moved upwardly. A spring-pressed pawl *h''* shown in dotted lines Fig. 2 is pivoted to a stationary part of the machine and arranged to engage the wire below the block *h* to prevent the wire from being moved backwardly by the upward movement of said block. The block *h* is loosely sustained and may be reciprocated in a groove *i* formed in the frame *c*, the block being retained loosely in said groove by a cover plate *i'*. An arm *i''* is extended from the block *h* into the pathway of the driver carrier *g'*, and said block is moved upwardly thereby as the driver carrier and driver are elevated. The block *h* is moved downwardly normally by a spring *j* connected at one end with a stud *j''* extended from said block through a slot in the cover plate *i'*, the lower end of said spring being connected with a suitable stud on the cover plate. The block in its descent through the action of the spring is arrested by an adjustable stop *j'* attached to the plate *i'* by means of a screw *n*, see Fig. 1, said stop being slotted at *n'* for the reception of said screw. By adjusting this stop the extent of the downward movement of the block may be regulated to correspond

with the distance it is desired to feed the wire and by adjusting this stop any desired length of nail or fastening can be obtained. The wire is fed from the block h through a 5 groove k into a perforation k' shown by dotted lines made in a stationary block k^2 , see Fig. 2, having a groove m in which is reciprocated a nail carrier m' through a lever f' , the lower end of which engages 10 said nail carrier. While the nail carrier remains in its outer position from the driver, a perforation m'' of said carrier shown in dotted lines Fig. 2 is in line with the perforation k' and the wire feeding mechanism 15 is timed to feed the wire through the perforation k' and into the perforation m'' . After the wire is fed into the perforation m'' the nail-carrier is moved toward the driver, and it will be readily seen that a 20 nail will be severed from the wire, and as the nail-carrier is continued in its movement the severed nail is carried forward in the perforation m'' until it is in line with the driver, where it remains while the driver 25 enters the perforation or nail guide m'' and drives the nail into a perforation left by the awl in the stock.

Having thus described my invention, what I claim is:

30 1. In a machine of the class described, fastening inserting mechanism, fastening forming mechanism, and means for feeding wire to said last-named mechanism comprising a block carrying wire-engaging pawls, 35 a guide for said block, means for moving said block in the direction to feed the wire to said fastening forming mechanism, and separate means comprising an element of 40 said fastening inserting mechanism for positively restoring said block to its initial position.

45 2. A machine of the class described, having in combination, fastening inserting mechanism, fastening forming mechanism, and means for feeding wire to said last-named mechanism comprising a block carrying wire-engaging pawls arranged to engage the wire at successive points, a guide for said block, yielding means acting normally to move said block in the direction to 50 feed the wire to said fastening forming mechanism, an adjustable stop for determining the amount of feeding movement of said block and separate means comprising 55 an element of said fastening inserting mechanism for positively restoring said block to its initial position.

60 3. A machine of the class described, having in combination, reciprocating fastening inserting mechanism, fastening forming mechanism and means for feeding wire to said last-named mechanism comprising a block provided with a wire-guiding opening, a plurality of spring-pressed pawls arranged to engage the wire in said opening 65

at a plurality of successive points and to lock it against one side of said opening, when said block is moving in the wire feeding direction, yielding means acting normally to move said block in said wire feeding direction, adjustable means for determining the amount of wire feeding movement of said block and independent means comprising an element of said inserting mechanism for restoring said block to its initial 75 position.

4. In a nailing machine, a driver bar having a driver, a stationary wire guide, a carrier having a hole to receive the end of the wire from the wire guide, a loosely 80 sustained block having pawls to act on the wire, a guide for said block, means to actuate said driver bar, said driver bar acting on the block to lift it, a spring to move said block downwardly that the pawls engaging 85 the wire may feed the end thereof into the hole in said carrier, and means to actuate said carrier to form a nail and put the same in the path of movement of the driver.

5. In a nailing machine, a driver bar having a driver, a stationary wire guide, a carrier having a hole to receive the end of the wire from the wire guide, a loosely sustained block having pawls to act on the wire, a guide for said block, means to actuate said 90 driver bar, said driver bar acting on the block to lift it, a spring to move said block downwardly that the pawls engaging the wire may feed the end thereof into the hole in said carrier, means to actuate said carrier 95 to form a nail and put the same in the path of movement of the driver, and adjustable means to regulate the extent of downward movement of said block under the action of its spring to thereby regulate the length of 100 the nail to be made.

6. A machine of the class described, having in combination, fastening inserting mechanism, fastening forming mechanism, and means for feeding the wire to said last-named mechanism comprising a block to engage one side of the wire, wire-engaging means carried by said block to engage the opposite side of the wire to clamp the latter for forward movement, a guide for said block, means associated with said block and comprising an element of said fastening inserting mechanism for lifting the block to effect a movement of the wire-engaging means carried thereby over the wire, yielding means tending normally to move said block in the wire feeding direction, and an adjustable stop to arrest the movement of the block in said wire feeding direction.

7. In a nailing machine, a driver bar, a 125 driver carried thereby, means to actuate the driver bar, a reciprocating wire-feeding block having wire-engaging means, said block having a projection to be engaged by the driver bar as the latter ascends, auto- 130

matically-operative means to cause the wire-feeding block to descend and thereby feed the wire, and an adjustable stop to limit the downward movement of the block.

- 5 8. In a nailing machine, a driver-bar, means to actuate it, a reciprocating wire-feeding block having wire-engaging means, said driver-bar acting on the block to give it its backward movement, automatically-operative means to give said block its forward movement to feed the wire, and an ad-

justable stop to be engaged by said block to limit the forward feeding movement thereof.

In testimony whereof, I have signed my 15 name to this specification, in the presence of two subscribing witnesses.

SOLOMON M. CUTTER.
